UNITED STATES PATENT OFFICE.

ELMER FRITJOFF STROMBERG, OF BOSTON, MASSACHUSETTS.

MUSICAL INSTRUMENT.

Application filed October 18, 1926. Serial No. 142,248.

This invention relates to banjos and instruments of like type, and has for its principal objects the improvement of tone qualities both as to volume and brilliance, and the improvement of structure as to certain mechanical features.

The matter of quality and volume in instruments of this type becomes of high importance in the case of public performance, and especially so where the instruments are played in orchestras furnishing music for dances and like entertainments. The principles involved in my invention, as well as the mechanical features, are illustrated in the accompanying drawings, to which reference is made by conventional characters similarly employed throughout.

In these drawings:

Fig. 1 is a view of the banjo head partly broken away to expose underlying structure.

Fig. 2 is a section through such head on an indicated line 2—2 of Fig. 1, and

Fig. 3 is an enlarged sectional view through one side of the head.

In the drawings I indicate at 1 the usual head frame provided with a metallic casing 2. This is a band usually surrounding the wooden frame 1, but as shown in Fig. 3 I preferably form this band with a spun-in portion 3 which is turned in and about a tubular ring 4.

Internally the ring 1 is rabbeted or shored as at 1' and on this shoulder rests an annular plate 5 soldered to a ring 6 which snugly fits within the frame 1. Supported on the ring 5 are a series of tubular members 7 apertured as at 7'. On these members 7 is a tone ring 8 over which the head or diaphragm proper H is stretched. The head is therefore drawn over the ring 8 within its margin and at its margin is drawn over the bead 3 on the metal shell 2. It is tightened by a hoop 9 pressed down by a follower 10. The hoop 9 is drawn down by the usual hooks or bolt wires 11 and is passed through the brackets 12 and receives the threaded nuts 13.

On opposite sides of the instrument I clamp beneath an opposed pair of the brackets 12 a plate 14. These receive the stems 15 threaded to receive the nut 16 and so holds in place the wall 17 with its resonator head 18 which is thereby drawn against the rubber buttons B on the bottom of the head frame 1. The resonator 18 is therefore de-

tachably connected to the instrument by simply removing the nuts 16.

When in place, the opening between the side wall 17 of the resonator is partially filled by the annular ring 19 which extends inwardly towards the outer wall of the banjo head, but does not touch it. This ring 19 is seated on an internal shoulder formed by rabbeting the upper edge of the resonator rim 17 and is provided with scallops 20 which clear the bolts 11 providing sound openings for the resonator below. The ring 19 is preferably made in four parts to provide clearance for the clamp plates 14, the neck N and tail-piece T.

The structure, as shown, while illustrative and capable of modification without departing from the spirit of the inventions involved, is a very satisfactory structure, both from the viewpoint of manufacture and that of performance. The tubes 7 supported on the plate 5 not only give a rigid support to the ring 8 but add individual and collective resonance to the instrument. This resonance is increased and multiplied in the resonator 18, which collects and controls the sound vibrations from within the head and generally directs them outwardly about the head, while in itself the wooden disc 18 constitutes a sounding board or amplifier. The bridge B and stringing S are merely indicated as of conventional type.

As heretofore suggested, a variety of modifications may be made in the various details shown, although individually and in combination the various elements cooperate to produce a strength and quality required for a public performance. Where strength or volume is not required, the resonator 18 may be quickly removed by unscrewing the nuts 16 and slipping the resonator from the instrument. This may be done without disturbing the tuning or the head tension and may be quickly and inconspicuously effected without material interruption in performance.

What I therefore claim and desire to secure by Letters Patent is:

1. In a banjo, a rim rabbeted internally to provide an annular seat, a plurality of tubular supports positioned on said seat, and a head ring disposed on the outer ends of said tubular supports.

2. In a banjo, a rim rabbeted internally adjacent its upper end to provide an annular

seat, a plurality of tubular supports positioned on said seat, and a head ring disposed on the outer ends of said tubular supports.

3. In a banjo, a head rim rabbeted internally to provide an annular shoulder, a ring fitted within said recess, a plate secured to said ring and resting on said shoulder, a plurality of relatively short upstanding apertured tubes supported on said plate and a tone ring mounted on the upper ends of said tubes.

4. In a banjo, a rim rabbeted internally to provide an annular seat, an annular plate positioned on said seat, a plurality of tubular supports positioned on said plate, and a head ring disposed on the outer ends of said tubular supports.

5. In banjo construction, a head, a head rim, stretcher brackets secured to said rim exteriorly thereof, head tightening members passing through said brackets, a pair of clamp plates secured to an oppositely disposed pair of said brackets, a resonator having a back and an enclosing rim of greater diameter than the head rim, a pair of resonator fastening members detachably connecting said plates to said resonator rim, and an annular ring seated on said resonator rim and scalloped to clear said head tightening members, thereby providing relatively unobstructed sound openings for the underlying resonator.

6. In banjo construction, a head, a head rim, stretcher brackets secured to said rim exteriorly thereof, head tightening members passing through said brackets, a pair of clamp plates secured to an oppositely disposed pair of said brackets, a resonator having a back and an enclosing rim of greater diameter than the head rim, the upper edge of said resonator rim being rabbeted to provide an internal annular seat, a pair of resonator fastening members detachably connecting said plates to said resonator rim, and an annular ring positioned on said seat and scalloped to clear said head tightening members, thereby providing relatively unobstructed sound openings for the underlying resonator.

7. In a banjo, a head rim rabbeted internally to provide an annular shoulder, a hori-

zontally disposed plate resting on said shoulder, a plurality of relatively short upstanding apertured tubes supported on said plate, a tone ring mounted on the upper ends of said tubes, a head stretched over said tone ring, a plurality of stretcher brackets secured to said rim exteriorly thereof below the lower ends of said tubes, a tightening hoop for said head, tightening members engaging said hoop and secured to said brackets, a pair of clamp plates secured to the under faces of an oppositely disposed pair of said stretcher brackets, a resonator having a back and an enclosing rim of greater diameter than the head rim, fastening members detachably connecting the resonator rim to said plates, and an annular ring positioned on said resonator rim and scalloped to clear said head tightening members, thereby providing relatively unobstructed sound openings for the underlying resonator.

8. In a banjo, a head rim rabbeted internally adjacent its upper end to provide an annular shoulder, a ring fitted within said recess, a plate secured to said ring and resting on said shoulder, a plurality of relatively short upstanding apertured tubes supported on said plate, a tone ring mounted on the upper ends of said tubes, a head stretched over said tone ring, a plurality of stretcher brackets secured to said rim exteriorly thereof below the lower ends of said tubes, a tightening hoop for said head, tightening members engaging said hoop and secured to said brackets, a pair of clamp plates secured to the under faces of an oppositely disposed pair of said stretcher brackets, a resonator having a back and an enclosing rim of greater diameter than the head rim, the upper edge of said resonator rim being rabbeted to provide an internal annular seat, fastening members detachably connecting the resonator rim to said plates, and an annular ring positioned on said seat of the resonator rim and scalloped to clear said head tightening members, thereby providing relatively unobstructed sound openings for the underlying resonator.

In testimony whereof I affix my signature.
ELMER FRITJOFF STROMBERG.
